UNITED STATES PATENT OFFICE.

JAMES H. BAKER, OF ALLEGHENY, PENNSYLVANIA.

DESIGN FOR A CHANNEL-IRON.

SPECIFICATION forming part of Design No. 28,863, dated June 14, 1898.

Application filed October 30, 1897. Serial No. 656,967. Term of patent 14 years.

To all whom it may concern:

Be it known that I, JAMES H. BAKER, a citizen of the United States, residing at Allegheny, in the county of Allegheny and State 5 of Pennsylvania, have invented and produced a new and original Design for a Channel-Iron, of which the following is a specification.

In the accompanying drawing, which makes part of this specification, the figure is an isometric perspective of the channel-iron.

In the view presented the shape is, generally speaking, channel-shaped in cross-section, having a flange A and a flange A', connected by a web B. The upper surfaces of 15 both flanges are rounded at a' and b'. The inner edge of flange A merges into the web B

on a curve substantially of the same radius as forms the upper surface of the right-hand flange.

The outer edges C C' of the channel-iron 20 converge toward the bottom of the piece and unite with the bottom of the channel-iron on rounded corners.

Having described my invention, I claim—

The design for a channel-iron, substantially 25 as shown and described.

In testimony whereof I have hereunto set my hand this 22d day of October, A. D. 1897.

JAMES H. BAKER.
